UNITED STATES PATENT OFFICE

HENRY J. ANDREWS, OF FORT WAYNE, INDIANA, ASSIGNOR, BY MESNE ASSIGNMENTS,
TO BLACK CLAWSON COMPANY, OF HAMILTON, OHIO, A CORPORATION OF OHIO

APPARATUS FOR REDUCING PAPER STOCK

Application filed April 11, 1927. Serial No. 182,862.

This invention relates to an apparatus for reducing paper stock and more particularly to an apparatus involving the use of a multiplicity of extractors or machines for the reduction of paper stock to pulp. These machines are commonly known in practice as tub beaters.

The invention contemplates the provision of two or more such machines connected in a series with means for conveying the reduced stock from one machine to the tub of the next adjacent machine. Fundamentally each machine consists of a tub or container for receiving the paper stock together with the necessary water or other liquids used in the process of production together with a receiver for the reduced stock which is delivered by centrifugal force to a perforated member through which the stock protrudes and is removed and deposited into the receiver.

This invention contemplates means for conveying the reduced stock from the receiver of one machine to the tub of another machine where this stock is again subjected to the action of the tub beater and the reduced stock again collected in the receiver. As a consequence of this arrangement stock may be placed in the first machine whereupon the reduced stock is collected and conveyed to the tub of the second machine whereupon the reduced stock is collected and conveyed to the tub of a third machine, etc., it being practical to provide as many tub beaters as found necessary, desirable or expedient. Thus the reduced stock delivered by each successive beater is correspondingly of a finer texture so that the grade of stock finally obtained may be governed by the number of machines connected in a series.

This invention has also as an object the provision of a mechanical conveyor with each tub beater for the purpose of removing the reduced stock from the receiver irrespective of whether a plurality of tub beaters are used or not.

The several objects, advantages and novel details of construction of this invention will be made more apparent as this description proceeds, especially when considered in con-

nnection with the accompanying drawing wherein:

Figure 1 is a sectional elevational view of an apparatus constructed in accordance with this invention, and

Figure 2 is an end elevation partly in section of the apparatus.

Referring now particularly to the drawing wherein like reference characters indicate like parts it will be noted that I have illustrated three paper stock reducing machines or tub beaters 10, 11, and 12. While these machines may be of any desired type or construction, the type herein illustrated and described is substantially similar to that type illustrated in United States Patents No. 1,244,144 granted October 23, 1917 to C. W. Unkle and T. D. Griley and No. 1,547,848 granted July 28, 1925 to C. W. Unkle. Inasmuch as the details of construction of the type of machine herein illustrated are described fully in the aforementioned patents it is only necessary herein to mention that each machine includes as a part thereof a tub 13 into which the stock to be reduced, together with the necessary water and other liquids used in the process, are placed. Each machine also includes a hood 14 within which a rotary beater (not shown) is arranged which throws the stock by centrifugal force against a perforated portion 15 of the hood. This perforated portion has associated therewith a stock remover which consists of a plurality of plates 16 adapted to be reciprocated between guides 17 by means of a rod 18. The rod 18 is reciprocated by a pitman 19 carrying a pin 20 working in the slot of a member 21 carried by the rod 18. Pitman 19 is operated by an arm 22 rotated by a worm wheel 23 driven by a worm 24 on a shaft driven by a pulley 25. As seen from Figure 2, pulley 25 may be driven by a belt 26 which engages a pulley 27 on a shaft 28. This shaft preferably extends transversely through the machine and carries the beater roll (not illustrated). A driving pulley 29 is mounted upon the other end of the shaft whereby the parts may be driven as will be obvious.

The reduced stock which protrudes through the apertures in the perforated portion 15

of the hood, is freed by the reciprocation of the plates 16 and is deposited in a gutter or receiver 30. The receiver 30 is provided with an extension or conduit 31 extending therefrom which is provided with a branch conduit 32. The branch conduit 32 of each conduit 31 communicates with the tub 13 of the next machine.

Extending longitudinally through the receivers of the series of machines is a conveyor 33, here shown as a spiral conveyor, operated by conveyor shaft 34. One end of the shaft 34 is here shown as provided with a pulley 35 by means of which the conveyor 10 may be driven, for instance, by means of a belt. It will be obvious, however, that any desired means for driving the conveyor may be provided. It will likewise be obvious that any other type of mechanical conveyor may 15 be utilized as well as any other type of means which will effect the transfer of the reduced stock from the receiver of one machine to the tub of the next.

In the structure herein illustrated, it will 25 be obvious that the reduced stock deposited in the receiver 30 of the first machine 10 will be moved from the receiver through the conduit 31 and will then pass through branch conduit 32 to the tub of machine 11. The 30 stock will then be acted upon in the customary manner by this tub beater whereupon a still greater reduction of the stock is obtained and this finely reduced stock delivered to the receiver 30 of this machine where again the conveyor transfers the same and deposits it 35 to the tub of machine 12 where the process is repeated. It will be immediately obvious to those skilled in this art that any number of machines may be connected in series and that 40 the texture of the stock will become increasingly fine depending upon the number of machines through which the stock is passed. The stock may be collected at the end of the conveyor beyond the last machine.

Obviously the herein described conveying apparatus may be used to advantage with single tub beaters for positively and quickly removing the reduced stock deposited in the receiver.

While one embodiment of the invention has been illustrated and described herein somewhat in detail it will be readily appreciated by those skilled in this art that various changes may be resorted to involving not only 55 the substitution of other types of paper pulp reducing machines but also any type of conveying apparatus and to this end reservation is made to make such changes in the specific construction illustrated as may come within 60 the purview of the accompanying claims.

What I claim as my invention is:—

1. In an apparatus for reducing paper stock, a plurality of tub beaters having aligned screen elements, the screen elements 65 having a continuous chute common to all the

beaters, said chute having outlets for the pulp screened from one beater leading into an adjacent beater.

2. In an apparatus of the character described, a plurality of tub beaters having a 70 series of screen elements, the screen elements having a continuous chute common to all the beaters, said chute having outlets for the pulp screened from one beater leading and depth of impressions formed thereby in 75 pulp conveyor in said chute.

3. In an apparatus for reducing paper stock, a plurality of tub beaters arranged adjacent one another in a series, said tub beaters having a series of aligned hood 80 screens arranged adjacent a continuous receiving passage having outlets for the pulp screened from one beater leading into an adjacent beater and a mechanically operated pulp conveyor in said passage. 85

4. In a continuous system of pulp preparation, a plurality of beater engines arranged side by side in a series at a common level and each including a beater roll simultaneously discharging coarse and fine 90 pulp material from the periphery thereof, a substantially horizontal trough and a continuous mechanical conveyor therein, said trough and conveyor connecting succeeding beater engines with one another, said trough 95 being located within the range of pulp centrifugally discharged from the beater rolls and having spaced outlets for discharging pulp received from the beater rolls into succeeding beater engines. 100

In testimony whereof I affix my signature.
HENRY J. ANDREWS.

CERTIFICATE OF CORRECTION.

Patent No. 1,903,526.

April 11, 1933.

HENRY J. ANDREWS.

It is hereby certified that error appears in the printed specification of the above numbered patent requiring correction as follows: Page 2, line 75, claim 2, strike out the words "and depth of impressions formed thereby in" and insert instead "into an adjacent beater, and a mechanical"; and that the said Letters Patent should be read with this correction therein that the same may conform to the record of the case in the Patent Office.

Signed and sealed this 23rd day of May, A. D. 1933.

M. J. Moore.
